CLAIM

The ornamental design for a shoe, as shown and described.

DESCRIPTION

FIG. 1 is a front top perspective view of a shoe showing my new design;

FIG. 2 is a front bottom perspective view thereof;

FIG. 3 is a bottom view thereof;

FIG. 4 is an opposite side rear top perspective thereof; and, FIG. 5 is a rear bottom perspective view thereof.

The broken line showing of the lightning bolt-shaped region forms no part of the claimed design. The broken lines depicting the remainder of the shoe form no part of the claimed design.

1 Claim, 5 Drawing Sheets(56)
